JOHN GRANT, OF LOS ANGELES, CALIFORNIA

GUARD FOR COLLAPSIBLE UNDERREAMERS

Application filed November 14, 1928, Serial No. 319,277. Renewed December 3, 1931.

This invention relates to collapsible underreamers and more especially to means for protecting the cutters from damage while in collapsed position and during passage through the well casing string.

Underreamers of the collapsible type having laterally projectable cutters are in many instances so disposed on the underreamer body as to ride along the well casing while being lowered. The well casing string is thus subject to damage by cutting, but the cutters themselves are subject to greater damage due to wear and abrasion as a result of the frictional dragging contact with the well casing string. This causes dulling of the edges of the cutters making them less efficient.

The present invention contemplates means to guard and hold the cutters from contact with the casing string. It is the primary object of this invention to provide such means so mounted that upon rotation of the tool they will be displaced enabling the cutters to fully expand and perform their cutting function without interference.

These objects together with other objects and corresponding accomplishments are obtained by means of the embodiments of my invention illustrated in the accompanying drawing, in which:—

Fig. 1 is an elevation of a complete underreamer with guards detached, the cutters being in expanded position; Fig. 2 is an axial section through the underreamer within a casing, the underreamer being in collapsed position and the guards mounted thereon; Fig. 3 is an axial section showing the cutters below a casing and in expanded position, the guards having been displaced; Fig. 4 is a section as seen on the line 4—4 of Fig. 2; Fig. 5 is a section as seen on the line 5—5 of Fig. 1, on an enlarged scale, the cutter spindle being shown in elevation and with a guard mounted thereon; and Fig. 6 is a perspective view of a guard.

Referring more particularly to the drawings, a body 7 has an upper pin adapting it for connection to a drill string and at the bottom has a detachable box 8 to receive the pin of a drilling tool or any other suit-

able device. Extending through the body is a circulation passage 9. Cutter accommodating cavities 10 are provided in the periphery of the body. These cavities have disposed therein cutters which are projectable into expanded position and retractable into collapsed position. At the upper ends of the cavities are pockets 11 to receive the upper ends of cutter spindles. Formed on the body and adjacent the pockets are inclined guide surfaces 12 for directing the spindles into the pockets. At the lower ends of the cavities are inclined bearing surfaces 13 for the spindles to bear against. Suitable vent holes are provided for the pockets to prevent trapping of circulation fluid therein, and courses connect with the circulation passage 9 to deliver wash water to the cutters and cavities.

There are four cavities shown herein, but there may be more or less, and in each cavity is mounted a cutter spindle 14. The cutter spindles are angled having knees 15 dividing each spindle into two journal sections for roller cutters. The lower ends of the spindles have bearing surfaces 16 for engagement with the corresponding bearing surfaces 13 on the body. These spindles are of such length that they may be moved longitudinally and bear at their lower ends against the surfaces 13. In the upper positions of the spindles, the lower ends are moved a slight distance outwardly. The upper ends of the spindles are in the form of fingers 17 which will snugly fit into the pockets 11. The ends of the fingers are inclined in a direction corresponding to the guide surfaces 12 as indicated by 18. In collapsed position as shown in Fig. 2, the fingers are out of the pockets and their ends are engaged with the guide surfaces. In expanded position, the fingers, as shown in Fig. 3 are disposed in the pockets. Mounted upon the journal sections are rotative cutters 19 suitably held in position by end collars.

The box member 8 is secured to the lower end of the body and provides a shoulder upon which a compression spring 20 is mounted. Slidably mounted over the box is a follower 21 of sleeve form arranged to

have the compression spring bear against it. Recesses 22 are formed by upstanding abutments on the follower so as to form seats or pockets for the lower ends of the spindles 14. The follower and spring tends to move the spindles upwardly and outwardly.

The underreamer may be collapsed by forcing the cutter mechanism downwardly so that the fingers 17 are out of their pockets 10 and the inclined bases of the spindles rest against the guide surfaces 13 as shown in Fig. 2. In this condition, the underreamer is inserted in the casing and may be lowered to reaming position. The casing serves to 15 maintain the cutters in collapsed position. When the underreamer has reached a position such that the cutters are below the lower ends of the casing, the compression spring expands, forcing the follower upwardly and 20 causing the inclined ends at the spindles to ride outwardly over the guide surfaces. When the fingers have reached registration with the pockets 11, they will slip therein and be in the position shown in Fig. 3. In 25 this position they are positively held against lateral movement with respect to the drilling axis of the underreamer.

It will be noted that without guards the cutters would ride against the casing when 30 disposed therein. This results in the cutting edges of the rollers being dulled while being lowered with resultant decrease of efficiency. To overcome this, I have provided each knee 15 with a groove 23. The upper and lower 35 walls of the grooves are preferably parallel, and the outer faces of the knees are flat. A guard is provided for each knee comprising a wear portion 24 to cover the knee and having a tongue 25 corresponding to the groove 40 23. The wear portion is of such thickness that when the guard is disposed in place upon its knee, the guard will extend laterally beyond the cutters and thereby hold them from contact with the wall of the casing. However, the ends of the grooves are 45 open so that upon rotation of the tool, the guards will be enabled to move circumferentially in relation to the underreamer and be displaced, dropping to the bottom of the hole. Displacement is caused by expansion 50 of the cutters and engagement of the guards with the side of the hole.

While a specific type of collapsible underreamer has been described herein, it will be understood that the invention is not limited to use with such species of underreamer. The specific type of underreamer has been described for illustrative purposes only. The invention is adapted to be embodied in other species of underreamers and in its broad aspect is not limited to underreamers having roller cutters. The scope of the invention is apparent from the appended 55 claims.

What I claim is:

1. The combination with a collapsible underreamer having a body and laterally projectable cutters, of guards projecting from the underreamer laterally beyond the cutters, said guards being mounted on said underreamer to be displaceable by rotational movement of said underreamer.

2. The combination with a collapsible underreamer having a body and laterally projectable cutters, of guards mounted on said underreamers by tongue and groove connections open at the ends so that said guards may be displaced by rotational movement of said underreamer, said guards extending 80 laterally beyond said cutters.

3. The combination with a collapsible underreamer having a body and laterally projectable cutters of guards on said cutters extending laterally beyond the latter, said guards being mounted on said cutters to be displaceable by rotational movement of said underreamer.

4. The combination with a collapsible underreamer having a body and laterally projectable cutters of guards mounted on said cutters by tongue and groove connections open at the ends so that said guards may be displaced by rotational movement of said underreamer, said guards extending laterally beyond said cutters.

5. The combination with a collapsible underreamer having roller cutters mounted on spindles projectable laterally of said body, of guards mounted on said spindles and extending laterally beyond the cutters, said guards being mounted on said spindles to be displaceable by rotational movement of said underreamer.

6. The combination with a collapsible underreamer having roller cutters mounted on spindles projectable laterally of the body, of guards mounted on said spindles by tongue and groove connections open at the ends so as to be displaceable, said guards extending laterally beyond said cutters.

7. The combination with a collapsible underreamer having cutters projectable laterally of said body comprising angled spindles extending longitudinally of said body, roller cutters journaled on said spindles, and guards mounted on the knees of said spindles so as to be displaceable by rotational movement of said underreamer.

8. The combination with a collapsible underreamer having a body with roller cutters projectable laterally of the body comprising angled spindles extending longitudinally of the body, roller cutters journaled thereon, and guards mounted on the knees of said spindles by tongue and groove connections open at the ends so as to be displaceable, said guards extending laterally beyond said cutters.

9. The combination with a collapsible un-

derreamer having a body and laterally projectable cutters, of guards projecting from the underreamer laterally beyond the cutters, said guards being mounted on the underreamer to be displaceable by frictional engagement with the side of the hole.

10. The combination with a collapsible underreamer having a body and laterally projectable cutters, of guards mounted on the cutters and projecting outwardly laterally therefrom, said guards being mounted on the cutters to be displaceable with reference thereto by frictional engagement with the side of the hole.

15. In witness that I claim the foregoing I have hereunto subscribed my name this 3rd day of November, 1928.
